UNITED STATES PATENT OFFICE

2,495,966

JOINT BETWEEN STRUCTURAL MEMBERS
OF BUILDINGSMalcolm E. Haines, Xenia, Ohio, assignor to The
McDowell & Torrence Lumber Company, Xenia,
Ohio, a corporation of Ohio

Application June 10, 1944, Serial No. 539,699

8 Claims. (Cl. 20—92)

1

My invention relates to buildings and in particular to the construction of a standardized building adapted to mass production.

It is a particular object of my invention to provide a system of joining the element of a building structure of the utmost simplicity but at the same time of such permanency and strength that the juncture point of the several elements of the building will constitute the stronger portion of the building instead of the weaker portion.

It is a further object to provide a system of reinforcement of the building to provide great strength despite the fact that this system of standardized interconnecting means is employed.

It is a further object to provide a standard system of mortise and tenon which can be produced on machinery in a mass production manner so as to reduce the cost of the standardized members.

It is a further object to provide a connecting system and means for effecting the connection between a plurality of building members so that not only are the members connected to one another but they are prevented from shifting with respect to one another while accommodating the expansion and contraction of the wood members constituting the building structure.

Referring to the drawings

Figure 1 is a perspective of the building embodying the construction of my invention with a portion of the side walls and the roof broken away to illustrate the method of the framing of the building and the nature of the completed attachment.

Figure 2 is a perspective showing the ridge pole and the roof supporting member in disassembled position together with the locking wedges just prior to assembling.

Figure 3 illustrates the same construction as shown in Figure 2 after it has been assembled.

Figure 4 is a detail of the horizontal and vertical framing of the building prior to assembly.

Figure 5 is a similar view after assembly.

Figure 6 is a perspective of one of the framing members showing the nature of the tapered wedges and the chamfer of the member in order to provide the tongue-and-groove wedging surface.

Figure 7 is a detailed illustration partially broken away of the juncture of the horizontal

2

and vertical framing member showing the nature of the tongue-and-groove welding construction.

Figure 8 is a perspective, partially broken away, showing one of the roof members, illustrating the nature of the wedge construction.

Referring to the drawings in detail, 1 is the foundation of a building upon which are mounted the bottom plate members 2 upon which are erected horizontal plate members 3 that serve to connect the studding 4 with the side walls and the framing members for the doors and windows as at 6 and 7. Mounted upon the studding 4 are the cap plate members 8. Mounted upon the cap plates are the rafters 9 and the ceiling joists 10. The rafters are interlocked with the multiple reinforced ridge pole member 11. The rafters and ridge pole carry the shingles 12.

Referring in detail to the construction of the building, it will be observed that the building is joined together to its several members by a mortise and tenon or a tongue-and-groove construction which consists of a building member generally designated a studding or a rafter which is provided at each end with a dovetailed member 16 having an outwardly flared wedged end 17 which forms a recess 18 into which is introduced either a flat plate or a wedge shaped plate 19 between the recess 18 and the slot 20 in the horizontal member such as the ridge pole member 11. The ridge pole member is made up of a central continuous plate 11a and side members 11b and 11c that may either be continuous or discontinuous but which are provided with a groove 20. In the event the members are discontinuous the ends of the members 11c are spaced from one another and adapted to receive the wedge shaped member 16. The wedges are sufficiently large to form a tight joint between the angularly disposed members in order to lock them together. By the reason of this construction the members can expand and contract and there is sufficient play to provide for this natural expansion and contraction without the parts becoming loosened. It will be noted that the several forms of contraction all employ a standardized type of tongue and wedge construction. It is preferable to have the groove 20 also tapered as in Figures 4, 5 and 7. Such a taper is indicated at 21. A single wedge 19 or dual wedges may be employed. In order to prevent the shifting of the horizontal

and vertical members with respect to one another vertically disposed or horizontally disposed intermediate grooves or notches 22 are provided in the walls of the groove 20. The member having the tongue is provided with the rib or tongue 23 that is insertable in the groove or notch 22. This provides against lateral movement between tongue-and-groove construction and leaves the wedge to perform simply the locking of the parts together to prevent their becoming detached by movement at right angles from one another. In this way the two pieces are anchored against movement at right angles to one another in either a horizontal or vertical direction.

By providing tongue-and-groove construction either on the sides or ends of the structural members, but still maintaining the tongue-and-groove construction of a standardized type, it is possible to develop a great variety of standardized forms of interconnection while retaining the advantages of a standardized method of production in order to reduce the cost of production and also retain the simplicity of assembly and disassembly of a standardized building to enable people of small ability in the construction of buildings to readily assemble their buildings at the minimum of cost with simple tools.

It will thus be seen that with the use of the hammer and screw driver it is possible to assemble or disassemble a complete building. All nails are eliminated. All sawing, dusting, cutting and fitting are eliminated and as the building is cut so as to accurately position the parts in their angular relationship it is unnecessary to do anything more than to provide the level foundation. After this has been provided, the structural members can be erected in a simple manner and as they are erected they provide a support for moving upwardly for the superimposition of additional members to finally complete the building and cover it. Any person of modest mechanical attainments can, therefore, completely assemble and erect a building and provide one that is true.

It will be understood that I desire to comprehend within my invention such variations of construction as are necessary to adapt my invention to various uses and conditions and which fall within the scope of the claims hereinafter appended.

Having thus described my invention, what I claim as new and desire to secure by Letters Patent, is:

1. In combination, a pair of building members one of which has a tapered groove convergent toward its open side and the other of which has an outwardly extending undercut tongue part disposed in said groove, a wedge between one side face of said tongue part and one side wall of said groove, said wedge and tongue filling said groove, and means for holding said building members rigidly in a direction along the length of said groove, said means comprising a rib on one of the other side faces of said tongue and a notch in the adjacent groove surface in which said rib rests.

2. In combination, a plurality of pieces of building timber abutting one another to form a joint of a building, one of said pieces having a tongue and another of said pieces having a tapered groove into which said tongue extends, said groove being of greater width than the width of said tongue, a wedge filling the space between the interlocking tongue and groove at one side, means for holding the pieces of timber rigidly in a direction along the length of the groove, said means

comprising a rib positioned at the faces of said first mentioned tongue and groove on the side opposite said wedge and extending angularly to the length of said first mentioned groove.

5. In combination, a pair of building members, one of which has an inwardly divergent groove therein and the other of which has an outwardly divergent tongue extending into said groove, one side face of said groove and tongue being parallel and abutting, a notch extending across one of said abutting faces, normal with respect to the direction of the tongue and groove, a rib in said notch and extending from the other of said abutting faces, and a filler member fitting between the other side faces of said tongue and groove and holding said first mentioned side faces in abutting relationship.

20 6. In combination, a pair of building members one of which has an inwardly divergent groove therein and the other of which has an outwardly divergent tongue which extends into said groove, said tongue and groove having one of their side faces parallel and in abutment, a notch extending across one of said abutting faces, normal with respect to the direction of the groove and tongue, and a rib extending into said notch and upstanding from the other of said abutting faces, and a filler member driven between the side faces of said tongue and groove on the side opposite said rib and notch, the largest part of said tongue being no greater in width than the narrowest part of said groove.

30 7. In combination, a pair of building members one of which has an inwardly divergent groove therein and the other of which has an outwardly divergent tongue extending into said groove, said groove and tongue abutting on one of the side faces thereof, a notch extending across the said one side face of said groove and at right angles to the length of said groove, a rib upstanding from the said one side face of said tongue and disposed in said notch, and a filler wedge driven between the other side faces of said tongue and groove.

40 8. In combination, a pair of building members one of which has an inwardly divergent groove therein and the other of which has an outwardly divergent tongue extending into said groove, said groove and tongue abutting on one of the side faces thereof, a notch extending across the said one side face of said groove and at right angles to the length of said groove, a rib upstanding from the said one side face of said tongue and disposed in said notch, and a filler wedge driven between the other side faces of said tongue and groove.

50 9. In combination, a building member having an inwardly divergent groove therein, a pair of other building members having outwardly divergent tongues extending into said groove and taken together being of less width than said groove, the outer faces of said tongues being parallel with and abutting the side faces of said groove, an interfitting rib and notch on at least one pair of said abutting faces and extending thereacross at an angle to the length of said groove, and a filler member between said other building members and positively retaining said other members in engagement with the side faces of said groove.

60 10. In combination, a building member having an inwardly divergent groove therein, a pair of other building members having outwardly divergent tongues extending into said groove and taken together being of less width than said groove, the

outer faces of said tongues being parallel with and abutting the side faces of said groove, interfitting ribs and notches on said abutting faces and extending thereacross at an angle to the length of said groove, and a filler member between said other building members and positively retaining said other members in engagement with the side faces of said groove.
